Primary Examiner — Susan Moon Lee*(74) Attorney, Agent, or Firm* — Young & Thompson**CLAIM**

We claim the ornamental design for an electronic camera, as shown and described.

DESCRIPTION

FIG. 1 is a front view of an electronic camera according to a first embodiment of the present design;

FIG. 2 is a rear view thereof;

FIG. 3 is a top view thereof;

FIG. 4 is a bottom view thereof;

FIG. 5 is a right side view thereof; and

FIG. 6 is a left side view thereof.

FIG. 7 is a front view of the electronic camera according to a second embodiment of the present design;

FIG. 8 is a rear view thereof;

FIG. 9 is a top view thereof;

FIG. 10 is a bottom view thereof;

FIG. 11 is a right side view thereof; and,

FIG. 12 is a left side view thereof.

The portions shown in broken line are not claimed.
